UNITED STATES PATENT OFFICE.

JAMES B. WALKER, OF RUSH SPRINGS, INDIAN TERRITORY, ASSIGNOR OF ONE-HALF TO ROBERT J. WALKER, OF WEIR, KANSAS.

DESIGN FOR A WORK-STAND.

SPECIFICATION forming part of Design No. 32,374, dated March 20, 1900.

Application filed February 15, 1900. Serial No. 5,386. Term of patent 7 years.

To all whom it may concern:

Be it known that I, JAMES B. WALKER, a citizen of the United States, residing at Rush Springs, in the Chickasaw Nation, Indian Territory, have invented and produced a certain new and original Design for a Work-Stand; and I do declare the following to be a full, clear, and exact description of the invention, such as will enable others skilled in the art to 10 which it appertains to make and use the same.

The invention relates to a new and original design for a work-stand; and it consists of a design of the shape and configuration shown in the accompanying drawing, in which I 15 have illustrated my invention in perspective.

The leading feature of the design comprises a rectangular base 1, from which rises a tapering standard 2, above which is located a circular tray 3, having radial wings 4, forming compartments 5, and provided with a ta-

pering standard 6 of greater diameter than the standard 2 and supporting a double truncated cone 7, from which project outwardly radial curved arms 8, supporting a ring 9, having upwardly-projecting spindles 10. Projecting upwardly from the double truncated cone is a rod 11, supporting a cup 12, provided with a cushion 13.

Having thus described the invention, what is claimed, and desired to be secured by Letters Patent, is—

The design for a work-stand, substantially as herein shown and described.

In testimony whereof I have hereunto set my hand in presence of two subscribing witnesses.

JAMES B. WALKER.
